UNITED STATES PATENT OFFICE.

HERBERT E. HILL, OF HAVERHILL, MASSACHUSETTS, ASSIGNOR TO THE REECE BUTTON HOLE MACHINE COMPANY, OF BOSTON, MASSACHUSETTS, A CORPORATION OF MAINE.

SEWING-MACHINE FOR FINISHING BUTTONHOLE-PIECES, &c.

No. 889,882.

Specification of Letters Patent.

Patented June 2, 1908.

Application filed March 26, 1908. Serial No. 423,326.

To all whom it may concern:

Be it known that I, HERBERT E. HILL, a citizen of the United States, and resident of Haverhill, county of Essex, State of Massachusetts, have invented an Improvement in Sewing-Machines for Finishing Buttonhole-Pieces, &c., of which the following description, in connection with the accompanying drawing, is a specification, like letters on the drawing representing like parts.

This invention relates to sewing-machines of the class wherein the work to be stitched is bent just before it is to be penetrated by the needle, in order that the needle may enter and its point emerge from the same side of the work to produce a "blind stitch." Such a machine, adapted to stitch down the "thrums" in button-hole pieces for boots, and shoes, forms the subject-matter of United States Patent No. 404,863 granted June 11, 1889 to John Reece. In said patent the work is intermittently bent or pressed into the groove of a throat-plate by means of a vertically reciprocated bender mounted on the overhanging arm of the machine adjacent the presser-foot, and operated by a cam and intervening connections, an eye-pointed needle being reciprocated horizontally transversely to the groove of the throat-plate, means being provided to impart to the needle a lateral motion in opposite directions at each alternate thrust, feeding mechanism of the usual four-motion type serving to feed the work in the direction of the length of the needle.

My present invention has for one of its objects the simplification of the stitch-forming mechanism in a blind stitch machine, whereby the lateral vibration of the needle-bar is obviated.

Another object of the invention is to provide novel bending means for the work, whereby the overhanging arm of the machine is dispensed with and the movement of the bender controlled by the feeding mechanism, acting in conjunction with a presser.

The various novel features of my invention will be fully described in the subjoined specification and particularly pointed out in the following claims.

Figure 1 is a top plan view of a sufficient portion of a sewing-machine for finishing

button-hole pieces, with one embodiment of my invention applied thereto, the cover-plate over the needle-actuating mechanism being removed; Fig. 2 is an end elevation thereof, a portion of the base of the machine being broken out; Fig. 3 is a view in elevation of the bender, bender-carrier and presser in inoperative position; Fig. 4 is an underside view of part of a button-hole piece, showing the thrums stitched in place by the blind stitching; Fig. 5 is a sectional detail on a large scale through the work in the direction of feed, showing the bend and the needles thrust therethrough; Fig. 6 is an under side view of the parts shown in Fig. 5, illustrating the two needles, and the shuttle-thread coöperating with the loops of needle-thread; Fig. 7 is a similar view, but with the needles retracted from the work, and showing the two lines of stitches interlocked within the material at each side of the thrum-ends.

Referring to Figs. 1 and 2 the bed-plate A, the main shaft A² driven in any usual manner and having a disk b² secured to its front end, the crank-pin b' on said disk, the link b pivotally connected at one end with the crank-pin; the shuttle c, (see dotted lines Fig. 1) the gathering plate d⁵ for the thrum-ends, mounted on the shuttle-cover d⁴; the throat-plate a' secured to the bed-plate and having a transverse groove a into which the work is bent or pressed intermittently, and the feed-bar d², having the usual serrated surface to engage the work and of the four-motion type, deriving its motion in usual manner from cams on the shaft A², may be and are all substantially as in the Patent No. 404,863 above referred to, and operate as therein set forth, the feed-motion cams being shown at b⁵, b² by dotted lines Fig. 1.

In accordance with my present invention the needle-bar 1 is mounted to reciprocate horizontally in bearings 2, 2 in a yoke-like frame 3 supported at 4, 5, Fig. 2, in the frame-work of the machine and held in fixed position by a bar 6 secured fixedly to the framework of the base A² by check-nuts 7, Fig. 1. A collar 8 fast on the needle-bar is 100 pivotally connected with the link b, whereby rotation of the disk b² effects longitudinal reciprocation of the needle-bar in its fixed bearings 2. The inner end of the needle-bar

has a clamp 9 in which are fixedly secured the shanks of two eye-pointed needles 10, placed side by side in parallelism with each other and with the needle-bar, said needles 5 being reciprocated transversely to the groove a in the throat-plate, the latter being slotted for the passage of the needles, as in the patent referred to. The bevel-faced needle-guide b^3 , pivoted at b^4 on the under side of the bed-plate A, is upturned into the slot, substantially as in said patent, and is acted upon by an arm 11 having a spring extension 12 adjustably held at 13, Fig. 1, a leaf spring 14 fast at one end on the under side of the arm 10 15 resting at its free end on the cam-shaped periphery of the disk b^2 , an adjusting screw 15 on the arm 11 acting upon the free end of the spring above the disk. As the needle points move toward the work the needle-guide b^3 is lifted and presents its beveled face close to the needle path as the needles are about to enter the work, so that the points of the needles cannot glance off the work, which at that time presents a convexed surface to 20 the entering needles. As the latter penetrate the work the guide b^3 is gradually lowered.

By using two needles side by side, to simultaneously enter and leave the work, each 30 needle carrying a thread, I dispense with any lateral vibration of the needle-bar to cause the single needle to penetrate the work first on one and then on the other side of the thrum-ends, for with the two needles the 35 loops of needle thread formed thereby are entered by and interlocked with the shuttle-thread, and two lines of blind stitching are formed, as shown in Figs. 4, 6 and 7. A much higher speed can be obtained, for the 40 needle movement is reciprocatory in the direction of the length of the needle-bar, only, and a very positive action is also attained.

In Fig. 6 the loops 10^x of needle-thread are entered by the shuttle-thread s , and as 45 the needles 10 are retracted the loops 10^x are drawn back into the material, see dotted lines Fig. 7, interlocked with loops s^x of the shuttle-thread, at opposite sides of the thrum-ends t , the blind-stitches when completed showing only at the under side of the work w , substantially as illustrated in Fig 4. As each opposite pair of interlocked loops is formed in the work the shuttle-thread crosses from one to the other line of stitching, as at s^2 , securing the thrum-ends securely in place.

The novel bender will now be described, and its manner of operation explained.

Upon the bed-plate A is secured by screws 60 16 a plate having ears 17 to receive a pin 18 on which is pivotally mounted a plate 19 which I term a base, having a limited rocking movement toward and from the bed-plate A on the pivot 18 at right angles to the

needle-path, a latch 20 pivoted on the bed-plate being adapted to hold the base down against the bed-plate, as in Figs. 1 and 2, when said latch is in the position shown in said figures. The free end of the base has fulcrumed upon it at 21 a bender-carrier 22, 70 shown clearly in plan, Fig. 1, and having rigidly attached to its free end a lateral, cylindrical arm 23 which projects across the feed-bar d^2 and has its end downturned to form a bender 24. Said bender is located 75 above the groove a in the throat-plate a' , and is given a vertical reciprocating motion to intermittently depress the work into the groove, to form bends, as w^x therein, each bend being formed just before the needles 10 80 are moved forward to enter the work. A strong leaf spring 25 is shown as fixedly secured to the top of the carrier 22 by screws 26, the free end of the spring bearing against the top of the base 19, the spring being so 85 arched that its constant tendency is to depress the free end of the carrier when the base is held by the latch 20 in its operative position, Figs. 1 and 2. When the latch is swung around to release the base the tension 90 of the spring is relaxed, and the base and carrier assume the relative positions shown in Fig. 3, and at such time the work can be readily inserted or removed. A presser roll 27 is rotatably mounted on the arm 23 above 95 the feed-bar d^2 , to travel on the upper side of the work w , Fig. 2, when the work is in position. Supposing the parts to be in operative position, as in Figs. 1 and 2, the pressure of the spring 25 acts to depress the 100 free end of the carrier and thereby the roll 27 bears firmly upon the work, and when the feed-bar descends the bender 24 acts to press the work down into the groove a of the throat-plate, to form the bend preparatory 105 to the forward stroke of the needles. The needles penetrate the work below the bender and the loops 10^x are entered by the shuttle-thread s , as in Fig. 6, and said needles are then withdrawn, the feed-bar moving to the 110 right, Fig. 2, while in its lowered position and then rising preparatory to the work-feeding stroke to the left. When the feed-bar rises it acts through the intervening work upon the presser roll 27, lifting it and the carrier 115 22, the latter rocking on the fulcrum 21, so that the bender 24 is raised as shown in Fig. 2, and the work is fed forward on the feed stroke of the feed-bar d^2 , the rotation of the presser roll permitting the work to pass 120 thereunder as it is fed. Then at the termination of the feed the feed-bar descends and the spring 25 depresses the free end of the carrier, causing the bender 24 to form the next bend in the work. It will be seen that 125 the bender is thus governed as to its reciprocating movement by the feed mechanism, being depressed by the spring 25 and elevated

by the rise of the feed-bar d^2 . This construction and arrangement does away with the overhanging arm for the bender and presser, and eliminates the cam and intervening devices for operating the bender, simplifying the construction and leaving the bed-plate clear for free manipulation of the work, as the bender-carrier and its base 19 are located at a sufficient distance from the 10 presser and bender to admit various widths of work.

The descent of the bender is limited by adjustable stop-screws 28 which are mounted on the carrier 22 and engage the bed-plate 15 when the spring 25 is free to act to depress the bender.

My invention is not restricted to a machine for finishing button-hole pieces, as will be manifest, nor to the precise details of construction and arrangement herein shown and described as the same may be modified or changed in different particulars without departing from the spirit and scope of my invention as set forth in the appended 25 claims.

Having fully described my invention, what I claim as new and desire to secure by Letters Patent is:

1. The combination, with a grooved 30 throat-plate, and a bender to intermittently bend the work into the groove, of stitch-forming mechanism including two parallel, eye-pointed needles, a horizontally reciprocating needle-bar on which the needles are 35 mounted, and means to reciprocate the needle-bar, feeding mechanism acting in the direction of the length of the needles, and means governed by said feeding mechanism to effect the operation of the bender.

2. In a sewing-machine, means to intermittently form bends in the work, stitch-forming mechanism including two parallel, eye-pointed needles, a needle-bar on which they are mounted, fixed bearings for the 45 needle-bar, and means to reciprocate the needle-bar at right angles to the bends formed in the work and to thrust the needles into such bends, combined with feeding mechanism acting in the direction of the 50 length of the needles, said feeding mechanism governing the operation of the bending means.

3. In a sewing-machine, the combination with a plate having a groove, and a bender 55 to intermittently bend the work into the groove, of feeding mechanism, means governed thereby to effect the operation of the bender, and stitch-forming mechanism including two needles mounted side by side, and means to reciprocate them in a path 60 transverse to the groove, to enter the bends formed in the work.

4. In a sewing-machine, a grooved throat-plate, stitch-forming mechanism, including

two needles mounted side by side, means to 65 reciprocate the needles in a horizontal path transverse to the groove, a bender to intermittently press the work into the groove, of the throat-plate, a feed-bar, and means governed by movement thereof to effect reciprocation of the bender.. 70

5. In a sewing-machine, a grooved throat-plate, a bender-carrier pivotally mounted adjacent the throat-plate, an arm extended laterally from the carrier and having a 75 downturned bender above the groove in said throat-plate, a spring to act upon the carrier to depress the bender and cause it to bend the work between it and the throat-plate, feeding mechanism, including a feed-bar, and 80 a roll on the bender arm above the feed-bar, to lift the bender intermittently while permitting feed of the work, combined with stitch-forming mechanism, including horizontally reciprocating needles to enter the 85 bends formed in the work.

6. In a sewing-machine, a grooved throat-plate, a bender to intermittently depress the work into the groove, a rocking bender-carrier fulcrumed adjacent the throat-plate, 90 a spring acting upon the carrier to operatively depress the bender upon the work, feeding mechanism, and means governed thereby to intermittently lift the bender and its carrier against the action of the spring. 95

7. In a sewing-machine, a bed-plate, a grooved throat-plate, a rocking bender-carrier fulcrumed adjacent the bed-plate, a laterally extended arm on the free end of the carrier, a downturned bender on the arm 100 above the groove in the throat-plate, a spring to depress the carrier and bender, feeding mechanism, including a feed-bar, and a presser roll rotatably mounted on the bender arm above the feed-bar, the latter 105 acting through the work upon said roll to intermittently lift the bender against the action of the depressing spring.

8. In a sewing-machine, a bed-plate, a bender-carrier having a laterally extended 110 arm provided with a depending bender, a base fulcrumed on the bed-plate and pivotally connected with the carrier, a spring fixed on the carrier and acting upon the base, a latch to hold the base down upon the bed-plate, to flex the spring and depress the carrier and bender, a throat-plate having a 115 transverse groove beneath the bender, depression of the latter pressing the work into the groove, a feed-bar, and means governed 120 by movement thereof to intermittently lift the bender-carrier and bender.

9. In a sewing-machine, a bed-plate, a grooved throat-plate, feeding mechanism, including a feed-bar adjacent the throat-plate, a rolling presser above the feed-bar, a spring-depressed support for the presser, having an attached bender above the groove. 125

in the throat-plate, and manually-controlled means to release the presser and bender from control of the spring and to place it under such control, the operation of the feed-bar 5 acting through the interposed work upon the presser and effecting intermittent lifting of the bender against stress of the spring.

In testimony whereof, I have signed my name to this specification, in the presence of two subscribing witnesses.

HERBERT E. HILL.
